GAS PRESSURE BLASTING DEVICE

Edward C. Filstrup, St. Joseph, Mich., assignor to Armstrong Coalbreak Company, Benton Harbor, Mich., a corporation of Michigan

Application March 16, 1951, Serial No. 215,974

6 Claims. (Cl. 102—25)

This invention relates to improvements in gas pressure blasting devices. More particularly the invention relates to a device adapted to be charged with and to confine a charge of gas at high pressure and provided with means operating automatically when the pressure of the gas reaches a predetermined value to permit a certain and instantaneous discharge of the gas through outlet passages therein. Devices of this character are commonly used in mining coal, being inserted in a drill hole in the face of the coal and being adapted, upon the instantaneous release of gas at high pressure, to break down the coal around the drill hole within which the device is mounted.

In the use of devices of this character, difficulty has been experienced heretofore by reason of the development of detrimental high temperature conditions incident to repeated or continued usage of the shell. The high temperature condition has been such as to injure the device, as by enlarging the size of discharge ports, or the like. A high temperature condition adjacent the discharge outlets may create a safety hazard inasmuch as tests reveal that, after a repeated number of successive operations, the discharge of gas may be accompanied by the emission of sparks. Another disadvantage of the tendency of the device to heat is that the device, when so heated, is difficult to handle manually.

Therefore, it is one of the primary objects of this invention to provide a device with novel protective cooling means for preventing development of excessive temperature conditions at parts of the device which are liable to injury or damage by such temperature conditions or at parts where high temperature conditions would create a safety hazard in the use of the blasting device.

A further object of the invention is to provide a device of this character with a novel, simple and inexpensive valve.

A further object is to provide a novel, simple and highly efficient blasting device which is easy to use, and simple to operate and to condition for operation.

Other objects will be apparent from the following specification.

In the drawing:

Fig. 1 is an axial sectional view of the device in its charging position.

Fig. 2 is an axial sectional view of the device in its discharging position.

Fig. 3 is an enlarged axial detail sectional view illustrating the connection of the cooling tube to the cartridge at the inlet port of the device.

Fig. 4 is a fragmentary detail view illustrating a modified embodiment of the invention.

Referring to the drawing which illustrates the preferred embodiment of the invention, the numeral 10 designates an elongated tubular rigid body formed of steel having a thick wall and capable of withstanding high gas pressures in the order of 15,000 to 20,000 pounds per square inch. This tube may be of any length desired, for example, it may be from a length of four feet to

2

a length of ten feet or more. In usual practice the diameter of the tube will range from two to three inches, although this tube size is stated as illustrative and is not intended to be limiting.

One end of the tube 10 is internally screw-threaded at 12 to receive an end member 14, here illustrated as having a cup-shaped externally screw-threaded flange portion 16. One of the parts 10 and 14, here illustrated as the cylindrical wall 16 of the end 14, has a circumferential groove adapted for the reception of a resilient annular sealing member 18 which may be of the type commonly known in the art as an "O-ring." The seal 18 is of such character that it tends to be deformed by pressure, so that the greater the pressure the greater will be the deforming and sealing action of the O-ring. The rear head 14 preferably has a shoulder 20 against which the rear end of the tube 10 abuts.

A reduced diameter externally screw-threaded end portion 22 is preferably formed on the part 14, said part 22 preferably having a coarse fast external screw-thread 24 formed therein and having threaded engagement with an annular internally screw-threaded wall 26 formed at one end of a protective tube 28. The tube 28 will preferably be provided with an inwardly projecting or annular end flange 30.

The rear head or end members 14 has a bore 32 extending substantially axially therethrough at its forward end and terminating in a screw-threaded bore portion 34 at its foremost part. Intermediate the longitudinal dimension or thickness of the part 14, the bore 32 is enlarged to define a shoulder 36. The rear end of the enlarged bore portion is screw-threaded at 38. A tubular fitting 40 fits snugly within the reduced bore portion 32 and has an enlarged frusto-conical tapered head 42 which seats against the shoulder 36 and presents its frustoconical surface 42 rearwardly.

A metal tube 44, preferably a thick walled copper tube, capable of withstanding very high pressures, extends through the central opening in the restricted flange portion 30 with clearance, and its front end is flared at 46 to tapered form having continuous bearing engagement with the tapered head 42 of the fitting 40. A tubular member 48 having a bore axially therethrough to receive the tube 44 with clearance is externally screw-threaded to engage the screw thread 38 of the head 14. The fitting 48 has a frusto-conical or flaring mouth 50 which serves to press the end portion 46 of the tube into the flaring shape shown. The arrangement is such that an effective gas-tight seal is provided between the tube 44 and the fitting 40. The fitting 40 has an axial bore 52 which communicates with the bore of the tube 44.

A fitting 54 has an externally screw-threaded end portion which has threaded engagement in the part 34 of the head of the bore 14. The fitting 54 has a bore 56 extending continuously therethrough and also is preferably provided with one or more lateral ports 58 which open the bore 56 of the fitting 54 into communication with the interior of the tube 10 around the fitting 54. The front end of the fitting 54 is externally screw-threaded and mounts an internally screw-threaded nut 60 having an annular flange 62 at its front end. The bore 56 of the fitting 54 is enlarged at 64 adjacent its front end and is adapted to receive the rear end of a tube 66. An annular retainer 68 encircles the end of the tube 66 and is pressed by the nut flange 62 in longitudinal direction against a flared portion of the socket of the fitting 54 whereby said part 68 is deformed radially inwardly and caused to fit into the tube 66 to anchor the same firmly in longitudinally extending and centered relation to the tube 10. The tube 66 preferably extends substantially full length of the tube 10, although it may terminate slightly short thereof as illustrated.

The front end of the tube 10 is preferably internally screw-threaded at 70 to receive a tubular adapter 72. The tubular adapter 72 has an intermediate portion of substantially the same diameter as the tube 10 and reduced end portions. The reduced end portion 74 is externally screw-threaded to fit in the screw-threaded portion 70 of the tube 10, with the end of the tube 10 preferably bearing against the shoulder between the parts 72 and 74 of the adapter. A leak seal is provided between the tube and the adapter part 74, preferably in the nature of an annular resilient sealing ring 76 seated in a circumferential groove of one of the parts and being of the character adapted to deform under pressure for the purpose of effecting a seal to prevent the leakage of gas therewith. The opposite reduced end portion 78 of the tubular adapter is externally screw-threaded at 80 and may likewise be provided with a circumferential groove to mount and receive an annular resilient sealing member or ring 82.

A tubular head 84 is internally screw-threaded at one end for screw-threaded engagement with the threads 80 of the adapter part 78. The head 84 is preferably of greater thickness than the body tube 10 as illustrated, and bears against the intermediate shoulder or enlarged part 72 of the adapter as shown. The joint between the adapter part 78 and the tube head 84 is rendered leakproof by the sealing member 82. In forwardly spaced relation to the front edge of the adapter 72, the tube 84 is preferably provided with a groove 86 which mounts the annular resilient sealing ring 88. The bore of the tubular head 84 is preferably reduced slightly forwardly of the groove 86 to define a narrow shoulder 90. A vent passage 92 opening to the exterior of the sleeve 84 may be formed adjacent to the shoulder 90 and at the large diameter side of said shoulder. In forwardly spaced relation to the shoulder 90, the sleeve 84 is provided with a plurality of large circumferentially spaced ports 94, here illustrated as inclined rearwardly and outwardly. It will be understood that the number of ports 94 may vary, but their number, size and arrangement is preferably such as to insure substantially instantaneous discharge of gas from the interior of the device when the ports 94 are opened. The head tube 84 is provided with a circumferential groove 96 forwardly of the ports 94, and this groove is designed to receive a resilient annular sealing ring 98. The front end portion of the head tube 84 is preferably provided with an enlarged bore portion defining a shoulder 100, and part of this bore may be internally screw-threaded at 102 at its mouth.

A forward head or end member 104 has a large diameter bore 106 formed therein for the major part of its length, said bore being reduced at an intermediate part 108 thereof defining a shoulder 110, and said bore having a smaller front portion 112. The head 104 has screw-threaded engagement with the threads 102 of the head sleeve 84 and preferably abuts the shoulder 100 at its rear end. An effective seal is provided between the head 104 and the head tube 84 in the nature of an annular resilient sealing ring 114, here illustrated as being mounted in a circumferential groove formed in the outer surface of the rear end portion of the head 104. The front end portion 116 of the head 104 has a large diameter internally screw-threaded bore formed therein, and is provided with a pair of diametrically opposed large apertures 118 spaced from its end edge. An annular washer or plate 120 seats in the bore in the front end 116 of the device, the plate 120 having an aperture therethrough substantially equal in diameter to the diameter of the bore part 112 of the head and in register therewith. Against the plate 120 is adapted to seat a shear member 122 which is introduced into the device through the aligned openings 118 in the head and which spans the bore 112. This shear member will preferably constitute a nail although any other rod, sheet or bar of suitable size and strength may be employed. The

size and strength of the shear member may vary as desired and will control the operating characteristics of the device as hereinafter explained.

The shear member 122 is normally clamped in position by an end plug member 124 having an axial passage 126 therethrough of a diameter equal to or preferably slightly larger than the diameter of the bore 112. The plug 124 is externally screw-threaded for detachable screw-threaded engagement in the end portion 116 of the head 104, and the front end portion 128 of the plug 124 is preferably enlarged and may be knurled to facilitate manual manipulation to tighten and loosen the plug 124. At its rear end the plug 124 is cup-shaped, being provided with an axial socket into which fits an annular member 130 having a cylindrical rearward projection 132 extending beyond the rear end of the plug 124. A snap ring 134 may serve as a means to lock the ring 130 within the socket of the plug 124 and to permit rotation of the parts 124 and 130.

A sleeve valve 136 is slidable in the tubular head 84 between the positions illustrated in Figs. 1 and 2. As best illustrated in Fig. 1, the sleeve is of a length to span the outlet passages 94 and also to span the groove 96 and terminates in rearwardly spaced relation to the outlets 94. The annular resilient sealing member 98 serves as a seal to prevent leakage around the right-hand end portion of the sleeve 136. One end of the sleeve valve 136, here illustrated as the left-hand end, has an annular wall 138, and this annular wall is provided with one or more large openings 140 extending therethrough, and also is provided with a central opening. An elongated valve stem 142 of a diameter having a snug sliding fit in the bore 112 of the head is mounted in the central opening in the end wall 138 of the valve sleeve 136. The valve stem 142 has an abutment or shoulder 144 adjacent one end and bearing against one surface of the sleeve valve end wall 138 inwardly of the apertures 140. The rear end portion 146 of the stem is preferably screw-threaded and has clearance within the opening in the wall 138. A nut 148 is threaded on the stem portion 146 and serves to secure the stem 142 to the sleeve valve 136. A slight clearance of the parts will be provided for purposes to be described, such that the sleeve valve may have a slight movement or tilting action relative to the stem 142. The stem 142 will be of such a length that, when the sleeve valve 136 spans and seals or closes both the outlet openings 94 and the groove 96, its front end will engage and bear against the shear member 122. One or more coil springs 150 preferably encircle the stem 142 bearing at their rear ends against the shoulder 144, and bearing at their front ends against an annular plate 152 seated against the shoulder 110. The member 152 cooperates with the bore part 108 of the head 104 to define a groove within which one or more annular resilient sealing members 154 are received and confined in a manner to insure against leakage of gas under pressure around the plunger 142.

A follower sleeve 156 is positioned between the end of the part 78 of the adapter and the end of the sleeve valve 136. The follower sleeve 156 is of greater thickness at the end thereof facing the intake of the device than at its opposite end, and a shoulder 158 is formed in its outer periphery and is adapted to seat against the shoulder 90 to limit travel of the follower. The sleeve 156 has a limited amount of free play or tolerance in its fit within the tube head 84 for purposes to be described. It will be observed that the annular resilient sealing ring 88 prevents the leakage of gas under pressure lengthwise of the follower sleeve at its outer surface. Consequently, the follower sleeve is subject to the application of a greater effective force to move it to the right than the force exerted to move the same to the left. It will be observed also that no seal is provided for the right-hand end of the follower sleeve, that is, between the vents or outlets 92 and 94. At its right-hand end the

follower sleeve 156 is reduced in diameter externally to provide a comparatively narrow annular lip 160. The annular lip has a flat edge lying in a plane transverse of the sleeve, as here shown, and the end wall 138 against which it bears, as illustrated in Fig. 1, also is flat and extends transversely of the axis of the sleeve valve 136, but it will be understood that the abutting valve-defining surfaces may take any shape found suitable or desirable.

In the use of the device it is placed in a hole drilled in the face of the coal to be broken down, the device having installed therein a shear member 122. The shear member is installed very easily by simply inserting it through the openings 118 when the cap or plug 124 is loosened, and then tightening the plug. The shear member may take any form found suitable, and one common form which is particularly well suited for use in the device is a nail, such as an 8-penny nail or a 10-penny nail. It will be understood that the line 44 is connected to a source of gas, preferably air under pressure, such as an air compressor, or an air supply system including one or more compressors and one or more receivers. The capacity of air pressure of the system should be in excess of the air pressure at which it is desired that the blasting device shall shoot or discharge. In use in coal mines where it is desirable to shoot at pressures ranging from 7,000 to 10,000 pounds per square inch, depending upon the structure of the coal and the conditions in the mine, the compressor or fluid supply systems should be capable of supplying air at pressures at 10,000 to 12,000 pounds per square inch. After the shell has been inserted in the drill hole, the operators retire to a safe distance from the working face, and preferably behind a post or in a side passage, and the valve (not shown) for controlling the supply of gas through the inlet line 44 is opened to charge the device by filling its hollow body with high pressure air.

As the air pressure in the device increases, it applies a force upon the working mechanism of the device acting toward the right and entailing the application of pressure to tend to cause the plunger 142 to shear the member 122. It will be apparent that the pressure in the device is uniform throughout, and, in this connection, it will be observed that the ports 140 permit free passage of gas through the device so that the pressure in the device at the right of the sleeve valve 136 is equal to the pressure in the remaining portions of the device. This results in the application of force tending to shear the member 122 which is of a value determined by the cross-sectional area of the aperture 112 multiplied by the pressure of the charge within the container. This pressure is supplemented by the force acting toward the right, as viewed in the drawing, equal to the difference in the force applied at the opposite ends of the follower sleeve 156. Actually, the value of this force is equal to the area of the shoulder 158 of the follower sleeve 156 multiplied by the charging pressure. Inasmuch as the large area end of the follower sleeve is located at the left, the pressure effective upon the follower sleeve serves to move it toward the right, that is, toward the sleeve valve 136, and this force adds to the force acting upon the end of the stem 142.

When the sum of the two effective forces is sufficient to cause the plunger 142 to shear the member 122, the valve sleeve 136 shifts toward the right to the position illustrated in Fig. 2, clear of the ports 94. At the same time the pressure forces the follower sleeve 156 to move toward the right to the extent permitted by the spacing between the shoulders 90 and 158, as viewed in Fig. 1. When the shoulder 158 engages the shoulder 90, the sleeve 156 stops and, as seen in Fig. 2, this section occurs before the follower sleeve can move a distance sufficient to cover the ports 94. The ports 94 are thus left open and the gas of the charge is substantially instantaneously exhausted therethrough. The instantaneous discharge of the gas, when at a pressure in the range from 7,000 to 10,000 pounds, and assuming that the device has a chamber

several inches in diameter and of a length of from four to ten feet, is effective to break down the coal around the device.

Since this device operates at high pressures, the retention of the gas charge is important. The use of O-rings or other seals at points 18, 76, 82, 114 and 154 insures that at points at which leakage could be expected incident to joining or connection of parts, such leakage will be avoided. It is necessary, of course, that there shall be an effective seal associated with the sleeve valve 136. The O-ring 98 provides such a seal at one side of the ports 94. The O-ring 88 provides such an effective seal at the other side of the ports 94. It will be observed, however, that inasmuch as the parts 136 and 156 are separate parts, any leakage of gas therebetween would be free to leak therearound either to the discharge ports 94 or to a vent port 92. In this connection it will be remembered that the sleeve valve 136 has a slight clearance in the bore of the head tube 84 and has a slight amount of play upon the stem 142. Under such circumstances the sleeve 136 is enabled to assume a position which will insure a continuous sealing engagement between the end face of the reduced diameter part 160 and the surface of the end wall 138 of the valve sleeve. It has been found that a metal-to-metal butt contact under these conditions, assuming that the faces contact each other continuously, will define a valve preventing leakage of gas between the abutting surfaces. This is particularly true where the wall thickness of the sleeve 156 at 160 is reduced, as to one-sixteenth of an inch or less. It will be understood that the thickness of the annular lip 160 preferably will be sufficient to enable it to withstand, without damage thereto or distortion, the force exerted upon the sleeve 156 at the discharge pressure, which force, as previously mentioned, is the product of the maximum charging pressure times the difference in area between the maximum outer diameter of the sleeve and the inner diameter of said lip. By this means only two annular resilient seals 88 and 98 are required adjacent to the discharge ports 94.

After the charge has been substantially completely evacuated, that is, after the gas pressure has reduced to a value equal to or slightly less than the value of the force exerted by the compressed springs 150, said springs will automatically return the valve sleeve 136 to the position illustrated in Fig. 1. The broken parts of the shear member 122 can then easily be released, if necessary, by simply loosening the cap 124, and a new shear member 122 can be inserted and held in place by retightening the cap 124. The device is then ready for another operation. It will be understood that the attendant will operate the control valve (not shown) to close that valve as soon as the blasting device discharges and will hold the control valve closed until the device is provided with a new shear pin and is inserted in the next drill hole to be blasted or shot.

The high gas pressures at which the device is charged tend to have a heating effect thereon, and repeated discharge of the shell entails high frictional factors due to high velocity air flow, and the device becomes heated incident to usage. The temperatures developed become quite high and are such as to tend to destroy the effectiveness and the life of the various annular resilient seals 18, 76, 82, 88, 98, 114 and 154 which are employed in the device. The temperatures may also be high enough to damage or injure some of the metal parts of the device, for example, may cause undesired enlargement of the outlet ports 94 in a manner tending to weaken the construction or to render difficult the maintaining of an effective seal. High temperatures also may cause the discharge of sparks at ports 94.

I have found that the use of the tube 66 is effective to hold the temperature at vital or critical parts of the device to values which are low enough to avoid injury and to provide safety of operation. The tube 66 extends substantially full length of the body tube or casing 10 and terminates adjacent to the adapter 72 and the valve control

mechanism. As the air or other gas under high pressure is exhausted from the end of the tube 66 during the charging operation, it expands and exerts a cooling effect upon the right-hand end part of the device, including the adapter 72, the sleeve head 84, the valve sleeve 136, the follower sleeve 156, and the various annular resilient seals 76, 82, 88, 98, 114 and 154 located at the head end of the device. It is also desirable, for the purpose of protecting the seal 118 and for cooling the rear end of the shell which is grasped by the worker in handling the device, to provide a cooling means at that end of the shell. For this purpose one or more ports 58 may be provided as shown, which permit the exhaust of air and the expansion of air at the left-hand end of the shell with consequent cooling effect.

Devices equipped with such cooling means have been found to possess longer effective life and to provide better performance characteristics than shells which are not provided with such cooling means, and it also has been found that there is less possibility that the workmen may suffer a burn in handling the device than is true with shells not so equipped. It will be understood that the cooling action is effective only at the localized areas mentioned and that high temperatures develop throughout the major portion of the length of the body tube 10. Those temperatures are not critical at that particular point, however, and when the shell is properly handled so as to be gripped only at its opposite ends, the worker can avoid injury due to heating of the intermediate part of the shell.

When the device discharges through the rearwardly outwardly inclined discharge ports 94, the action of the gas urges the device forwardly. This movement is stopped when the inner end of the drill hole is contacted, and the device is therefore subject to severe impact or shock. This shock imposes severe strain and stress upon the cooling tube, tending to fracture the tube or to pull the tube from the fitting 60. This can be obviated, if desired, by providing yielding means which cushions the shock of instantaneous deceleration. One such yielding means may consist of a section of elastic or extensible hose or conduit 67, such as a metal reinforced conduit formed of rubber or rubber-like material incorporated in tube 66, preferably adjacent to the fitting 60, as seen in Fig. 4. The extension of the elastic section absorbs the shock upon the tube when the device is shot.

While the preferred embodiment of the invention has been illustrated and described herein, it will be understood that changes in the construction may be made within the scope of the appended claims without departing from the spirit of the invention. It will also be understood that the terms "forward" or "front," as used herein, refer to the right-hand portion of the item mentioned as viewed in the drawing; while the term "rearward," as used herein, refers to the left-hand portion of the item mentioned as it is viewed in the drawing.

I claim:

1. A gas pressure device comprising a hollow body having a lateral outlet and an end aperture, a shear member spanning said end aperture, a plunger slidable in said end aperture, a sleeve valve carried by said plunger and adapted to span said outlet, a differential area follower sleeve having a limited pressure responsive movement in said body and normally abutting said sleeve valve, a pair of annular resilient sealing members carried by said body in longitudinally spaced relation at opposite sides of said outlet, said sleeve valve and follower sleeve having abutting end surfaces engaging to define a valve preventing leakage of gas therebetween.

2. A gas pressure device comprising a hollow body having a lateral outlet and an end aperture, a shear member spanning said end aperture, a plunger slidable in said end aperture, a sleeve valve carried by said plunger and adapted to span said outlet, a differential area fol-

- lower sleeve having a limited pressure responsive movement in said body and normally abutting said sleeve valve, a pair of annular resilient sealing members carried by said body in longitudinally spaced relation at opposite sides of said outlet, said sleeve valve and follower sleeve having abutting end surfaces engaging to define a valve preventing leakage of gas therebetween, said sleeve valve having limited play on said plunger to accommodate abutment of said last named valve-defining end surfaces.
3. A gas pressure device comprising a hollow body having a lateral outlet and an end aperture, a shear member spanning said end aperture, a plunger slidable in said end aperture, a sleeve valve carried by said plunger and adapted to span said outlet, a differential area follower sleeve having a limited pressure responsive movement in said body and normally abutting said sleeve valve, a pair of annular resilient sealing members carried by said body in longitudinally spaced relation at opposite sides of said outlet, said sleeve valve and follower sleeve having abutting end surfaces engaging to define a valve preventing leakage of gas therebetween, said sleeve valve having limited play on said plunger to accommodate abutment of said last named valve-defining end surfaces, each of said sleeve valve and follower sleeve having limited clearance in said body.
4. A gas pressure device comprising a hollow body having a lateral outlet and an end aperture, a shear member spanning said end aperture, a plunger slidable in said end aperture, a sleeve valve carried by said plunger and adapted to span said outlet, a differential area follower sleeve having a limited pressure responsive movement in said body and normally abutting said sleeve valve, a pair of annular resilient sealing members carried by said body in longitudinally spaced relation at opposite sides of said outlet, said sleeve valve and follower sleeve having abutting end surfaces engaging to define a valve preventing leakage of gas therebetween, said follower sleeve having a reduced diameter end portion engaging said sleeve valve, said valve-defining surface being formed at the end of said reduced diameter portion.
5. A gas pressure blasting device comprising a hollow body having a lateral outlet and an end aperture, a shear member spanning said end aperture, a plunger slidable in said end aperture, a sleeve valve carried by said plunger and adapted to span said outlet, a differential area follower sleeve having a limited pressure responsive movement in said body and normally abutting said sleeve valve, a pair of annular resilient sealing members carried by said body in longitudinally spaced relation at opposite sides of said outlet, said sleeve valve and follower sleeve having clearance in said body and cooperating valve defining abutting surfaces normally positioned between said resilient sealing members.
6. A gas pressure blasting device comprising a hollow body having a lateral outlet and an end aperture, a shear member carried by said body and spanning said end aperture, a plunger slidable in said aperture, an annular resilient sealing member encircling said plunger at said aperture, a sleeve valve carried by said plunger and adapted to span said outlet, a pressure responsive follower sleeve in said body, said sleeve and sleeve valve having abutting valve-defining surfaces, means limiting movement of said follower sleeve in said body, and longitudinally spaced sealing means encircling said sleeves and positioned at opposed sides of said outlet and of said valve-defining surfaces.
